JAKOB REGENSTREIF, OF BERLIN, GERMANY, ASSIGNOR TO GENERAL ELECTRIC COMPANY, A CORPORATION OF NEW YORK

FILAMENT-MOUNTING MACHINE

Application filed May 3, 1928, Serial No. 274,877, and in Germany May 17, 1927.

The mounting of coiled filaments of electric incandescent lamps on anchors extending radially from the stem and having loops or eyes on the ends has sometimes been done by auxiliary devices operated automatically with the object of saving labor. The principal object of this invention is to provide means for automatically mounting the coiled filaments by simple mechanism and in a very reliable manner. To this end the filament is threaded thru the anchor loops by a threading device comprising a filament former or shaper which comprises a filament feeder with a feed conduit or groove preferably straight and of a cross section or bore corresponding to the cross section of the filament, and serving both for feeding and straightening the filament, and also a filament guide with a curved guide conduit of the same bore which adjoins the outlet of the feed conduit and acts as a bridge between the loops or hooks of the anchors on the stem lowered into the filament shaper. By this novel arrangement a filament placed in the feed conduit may be slid endwise by a pusher or by air under pressure, or by suction, into the curved guide conduit along which it is pushed or pulled so that it slides along the conduit endwise and is threaded thru the loops of the anchors on the stem. To facilitate the threading of the filament thru the loops of the anchors that part of the filament former having the feed conduit, as well as that part having the curved guide conduit, are both preferably made in two separable parts to facilitate introducing the filament and confining it closely in the conduits.

The invention may advantageously be embodied in the usual hook inserting machine of the kind which in several successive working positions inserts the loops or anchors radially into a glass bead on the stem rod or arbor, and furthermore produces loops or eyes on the free ends of the anchors for holding the filament. In such a machine there may be provided at a working position of the hook inserting machine following that one where the coiled filament is mounted on the stem by being threaded thru the anchor loops, a loop closing device comprising a vertically

movable punch cooperating with a stationary anvil to narrow down and more completely close the loops around the coiled filament and thus hold the filament.

One form of embodiment of the invention is shown in the accompanying drawing in which Fig. 1 is a top view of the filament former with a cover for the filament guide swung back out of the way; Fig. 2 is a cross section of the filament feed portion along the line II—II of Fig. 1; Fig. 3 is a section partly along the line III—III of Fig. 1; Fig. 4 is a section along the line IV—IV of Fig. 1; Fig. 5 is a section along the line V—V of Fig. 1; Fig. 6 is a top view, like Fig. 1, of a modification using air pressure to move the filament endwise; Fig. 7 is a cross section along the line VII—VII of Fig. 6; Fig. 8 is a section along the line VIII—VIII of Fig. 6 with the cover 14 in place on the block 3; Fig. 9 is a top view of the device of Fig. 6, modified to use suction instead of compressed air; Fig. 10 is a diagrammatic top view of a holder inserting machine provided with the filament mounting device constructed according to this invention; and Figs. 11 to 14 show diagrammatically certain details of the holder inserting machine and of the stem produced on it.

In the particular embodiment of the invention shown in Figs. 1 to 5 the filament former which serves to receive the coiled filament 1 comprises a straight filament feeder with a long straight base block 2 associated with a curved filament guide comprising a curved or approximately semi-circular base block 3 associated with the feeder base block 2 or formed in one piece with it and having in its flat upper surface a curved guide groove or conduit to guide the filament into the anchor loops. The base block 2 has a wide straight channel with an inclined bottom 4 extending its entire length and a straight feed groove or conduit 5 along the lower edge of the sloping bottom 4 and forming a continuation thereof, the cross section of this conduit corresponding to but being slightly greater than the cross section of the filament. Each filament is placed in the feed conduit 5 by being passed sidewise and down along the 100

sloping bottom 4 from a supply of loose filaments, either by hand or mechanically. The straight feed groove or conduit 5 not only receives the filament 1, but also straightens it out into a straight line. A vertically movable cover 6 having an inclined bottom corresponding to the inclined bottom 4 of the channel in the block 2 as shown in Fig. 2 descends into the channel in the block 2 after the insertion of the filament thereby closing the straight part of the filament feeder and converting the groove 5 into a duct which encloses the filament with slight clearance.

The curved base block 3 has in its upper surface a curved guide groove or conduit 7 of a length corresponding to the length of the filament to be used. This groove 7 is crossed by transverse anchor slots or radial cuts 8, spaced from one another to correspond to the spacing of the loops 11 of the radial anchors 9 of the arbor 10 of the stem. To one side of the guide block 3 on a vertical shaft 12 is an arm 13, mounted to oscillate and also to move along the axis of the curved block 3 so as to be raised and lowered. This arm 13 has on its free end a curved cover or cap 14 for the curved guide block 3 and which, when the arm 13 is swung over the block 3 and lowered, rests on the guide block 3 as shown in Fig. 3 and covers or closes the guide groove 7 in the block and thus converts it into a closed and curved guide duct. The cap 14 also has radial slots 15 which register with the anchor slots 8 when the cap is in place, so that, as the stem is lowered along the axis of the curved block 3 and the cover 14, the loops 11 of the anchors 9 can pass through the slots in the cap 14 into the anchor slots 8 of the guide block 3. The depth of each anchor slot 8 is such that its bottom is slightly below the bottom of the groove 7, and therefore the anchor loop 11 resting on the bottom 16 of an anchor slot 8, as shown in Fig. 4, is concentric with and in registry with the groove or conduit 7 in the curved block 3 of the filament guide.

Two radial lead slots 17, one at the junction between the straight filament feed conduit 5 and one end of the curved guide conduit 7 and the other at the other or free end of the guide conduit are provided in the curved block 3 to receive the hooks 18 on the ends of the two leads 19 of the stem. Two radially movable clamping jaws 20 enter the lead slots 17 transversely of the leads and clamp the hooks 18 down on the ends of the filament 1. Each section of the curved guide conduit 7 for the filament has a funnel-shaped entrance 21 formed in the walls of the radial anchor slots 8 and facing the advancing end of a filament sliding along the guide conduit 7 in order to facilitate the pushing of the filament endwise thru all the sections of the guide conduit 7.

The operation of the device shown in Figs. 1 to 5 is as follows:

First the arm 13 is swung into place over the guide block 3 and then lowered until the cap 14 sets snugly on the upper flat surface of the curved block 3. Then the lamp stem, with its arbor 10 and radial anchors 9 provided with complete loops 11 is lowered until the hooks 18 on the leads are in the lead slots 17 and the anchor loops 11 are in the intermediate radial anchor slots 8 and resting on the bottom 16 of the radial anchor slots, which serve as stops for the loops 11 and prevent excessive lowering of the stem. At the same time with, or shortly after this downward movement of the stem, and while the cover strip 6 of the filament feeder is raised, a filament 1 is passed down the sloping bottom 4 of the channel in the feed block 2 into the feed conduit 5 and thereby straightened. Then the cover strip 6 is lowered into the channel in the block 2 until its inclined bottom rests on the sloping bottom 4 of the channel in the block 2 and then the filament 1 is slid endwise along the feed conduit 5 in the direction of the arrow in Fig. 1 by pressure exerted by the cylindrical push rod 22 fitting accurately into the conduit 5. The push rod 22 is of such a length that by its forward stroke the filament is pushed entirely out of the feed conduit 5 into the guide conduit 7 and slides endwise along said curved guide conduit 7 and thru the loops 11 resting in the anchor slots across the conduit until the forward or advancing end of the filament 1 is stopped by striking against the stop 23 extending across the guide conduit 7 at the end of the curved guide block 3. Both ends of the filament 1 are now in place in the lead slots 17 and in the hooks 18 of the leads 19. Immediately after the push rod 22 has pushed the filament 1 endwise into the curved filament guide and thus through the anchor loops 11 in the guide, the clamping jaws 20 move outwards and radially of the curved guide conduit 7 and close the hooks 18, thus clamping the leads to the ends of the filament. The arm 13, with the cover 14 attached thereto, is now lifted slightly and then swung to one side whereupon the finished mount may be lifted out of the curved filament guide block 3.

The modification shown in Figs. 6 to 8 is of much the same construction as that in Figs. 1 to 5, except that in this modification the filament is threaded through the loops of the anchors not by a push rod, but by air pressure. To this end air channels 24 are provided in both the filament feeder block 2 and the filament block 3 parallel to and at a slight distance from the straight feed conduit 5 and the curved guide conduit 7, and are at will connected to and disconnected from a source of air under pressure. In the feed block 2 the air channel or groove 24 is

covered air tight by a special cover strip 25 which is wedge shaped to provide a slanting bottom for the filament feed channel in the block 2 and in the guide block 3 it is covered by the cover 14 on the oscillating arm 13. 5 The channel 24 in the feed block is connected thru a nozzle-like port 26 with the inlet end of the feed conduit 5, which in this case does not extend entirely thru the feed block 2, as it does where a push rod is used to push the filament along the feed conduit. By this port 26 pressure is exerted by the air on the end of the coiled filament. In addition air is delivered at other points to the 10 feed conduit 5 at intermediate points from the air channel 24 by four ports 27 set to produce air jets which push the filament endwise along the feed conduit. The filament is also pushed endwise along the guide conduit 7 by 15 air jets produced by ports 28 leading from the parallel curved air channel 24 to the curved guide conduit 7 and discharging into the filament receiving end of each section of the guide conduit. As soon as the air blast 20 is sent in the direction of the arrow thru the air channel 24 the filament 1 enclosed in the guide conduit 5 is caught at the rear end and also at several intermediate points along its length by the air streaming from the ports 25 26, 27, and is moved endwise along into the curved guide conduit 7, where it is likewise caught by the air issuing from the ports 28 and is continually pushed along until it has moved entirely into the guide conduit 7 and 30 thru the anchor loops 11 of the stem and its forward end is against the stop 23 on the guide block 3. The ends of the filament 1 are now in position in the hooks 18 of the leads 19, and can be attached to the hooks by 35 moving the clamping jaws 20 into the lead slots. In order that the threading of the filament 1 thru the loops 11 of the stem and the transfer of the filament from one section of the curved guide conduit 7 to the next may 40 take place easily, the ports 28 are arranged to deliver directly across the radial anchor slots 8 and into the open or receiving end of each duct section. The forward or leading end of the filament is thereby each time 45 directly put in an anchor loop of the stem by air under pressure and is bent over toward the inner wall of the guide conduit so as to 50 come into the middle of the loop.

After the filament is blown into the guide 55 block 2 a single puff of air suffices to put it in its final position. In order, however, to increase the certainty of the placing of the filament a number of rapidly repeated puffs of air may be employed. These repeated 60 puffs or blasts may be obtained by alternately opening and closing the pressure air duct in various ways. In the particular example shown, the repeated air puffs or blasts are produced by a rotary valve 29 having near 65 the rim of a number of ports 30 and so

mounted in the pressure air inlet 31 of the filament feeder 3 that the ports 30 register with the air inlet and upon each revolution of the valve 29 the air under pressure is admitted to and shut off from the duct 24. 70

In the particular construction shown in Fig. 9 the filament 1 enclosed in feed conduit 5 of the part 2 of the former is conducted into the curved guide conduit 7 and the loops 11 of the stem by suction. In this case a 75 vacuum duct 24^a traverses the two parts 2 and 3 of the former parallel to and in communication with the feeding and guide ducts 5 and 7. The vacuum duct 24^a is connected to a suction pipe by a connection 32 on the semi-annular part 3 of the former. The suction ports 27 and 28 provided in the two parts of the former are set at an angle about 90° different from the pressure ports, and are nearly tangential to the curved guide conduit 7, 80 so as to be better adapted to cause the filament to be slid along the conduits by the flow of air from the outside through the ports and into the vacuum duct. The flow of air by suction for sliding the filament along the 85 guide conduit 7 can also be interrupted by a rotary valve, like the valve 29, at short intervals to produce puffs of air and thereby cause safer transmission of the filament along the 90 guide conduit. 95

The filament mounting mechanism above described and constructed according to the invention may be used independently of the usual intermittently rotated hook inserting machine of the kind in which loops are produced in the free ends of the radial anchor wires and thus complement such machines. It is, however, advantageous as shown diagrammatically in Fig. 10 to incorporate the described filament mounting mechanism into 100 such an intermittently rotating hook inserting machine. 105

The hook inserting machine shown diagrammatically in Fig. 10 may be constructed on the same general principle as that shown in the application for U. S. Patent, Serial No. 243,698, filed Dec. 30, 1927, by Ledig and Loebe, and makes one complete revolution in twelve steps. As shown in Fig. 3 the table 41 of the machine has a pedestal 42 in which is a vertical tubular shaft 43 having on the upper end a spider 44 in which stem heads 45 are mounted to move vertically. A push rod 46 in the vertical tubular shaft and actuated by a cam 47 on the drive shaft 48 lowers and raises the stem head at the working position. In work positions *a* and *b* the lamp stems produced in the stem making machine and consisting of the flare tube 33, the exhaust tube 34, the arbor 10 and the two leads 19 shown in Fig. 11 are placed in the vertically movable stem head 45 of the machine. In working position *c* the leads 19 are by a known mechanism, indicated diagrammatically and actuated from the drive 110 115 120 125 130

shaft, bent from their original vertical position to such an angle that in working position *d* for the preliminary heating position as well as in working position *c* for the fusing of the stem tube and making the press they 5 cannot be affected by the pointed flames 35, 36 used for heating the lower part of the stem tube to make the press. The arbor 10 with the drop of fused glass produced on its end by the pointed flames is lowered at working 10 position *f* to insert the anchors, the stem being lowered until the hot glass drop on its end encounters a stop and forms a bead which overflows and embeds the inner ends of the thin anchor wires 9 fed radially from supply 15 rollers, as in U. S. patent to Schluter 1,238,575, August 28, 1917. In the same working position the loops 11 at the ends of the anchor wires 9 are produced by a known hook bending mechanism as indicated in Fig. 11. 20 In the next working position *g* the leads 19 are bent by known mechanism, such as shown in the above identified Ledig and Loebe patent application, into that position in which they must stand in the finished lamp. In 25 the same working position the ends of the leads are pressed somewhat flat by the clamping jaws 37 indicated in Fig. 12 and operated from the drive shaft 48 by connections not shown. In the next working position *h* the 30 flat pressed ends of the lead are likewise bent over into hooks 18 as indicated in Fig. 13, by hook benders actuated from the drive shaft. In the next working position *i* there 35 is a filament mounting device constructed in accordance with the invention and as above described. In the following working position *k* there is a loop closing device, shown in Fig. 14, which comprises a fixed abutment 40 or anvil 38 curved to correspond to the curve of the mounted filament and a vertically movable similarly curved press block 39. When the stem with the filament mounted on it reaches this working position and is lowered 45 into the hook closing device the loops 11 of the stem are somewhat compressed by the downward movement of the press block 39, causing a contraction of the loop and a greater closure of the loops, because by the pressure exercised on the outer loop parts, the 50 upwardly projecting ends 40 of the anchor wires at the inner edges of the loops are moved outwardly as the loops are compressed. In working position *l* the filaments of the 55 stems are dipped into a suspension of a getter, such as a phosphorus mixture, to decrease the blackening of the lamp. Working position *m* is the discharge position at which the finished mount is taken out. 60 Since the various parts of the machine may be actuated in the desired sequence in many different ways, the driving mechanism is indicated diagrammatically and not in detail, but in general the drive shaft 48 moves the 65 spider step by step thru an intermittent gear

49, and the other mechanisms by well known connections. For example, the cover 14 of the filament guide is raised and lowered, and swung into and out of registry with the block 3 by a cam 50 on the drive shaft which 70 raises and lowers, through a push rod 51, the shaft 12 of the cover, which slides in a guide 52 on the pedestal 42. The shaft has a projecting pin 53 which moves in a guide slot 54 so shaped that during the first part of its upward movement the rod rises without turning, thereby lifting the cover 14 straight up, and during the latter part of its upward movement the rod is turned on its axis, so as to swing the cover to one side. On the downward movement of the rod the cover first 75 swings into place directly over and in registry with the block 3, and then drops straight down.

A similar mechanism controlled by cam 55 on the drive shaft actuates the press block 39 of the loop closing device through a push rod 56 and a guide 57 for the press block 80 shaft 58.

The clamping jaws 20 may as shown in 85 Fig. 5, be thrust into the lead slots 17 to close the hooks on the leads 19 by a wedge 59 thrust between the jaws 20 by a cam on the drive shaft 48.

The cover 6 of the filament guide may to 90 advantage be lifted automatically by a push rod 60 actuated from the drive shaft 48 to raise the cover and permit the filament to roll down the sloping bottom 4 into the feed conduit 5, and then lower it to confine the 95 filament in the feed conduit so that endwise pressure on the filament will not buckle or bend the filament, but will push it out of the feed conduit.

The valve 29 of the filament feeder may be 100 actuated from the drive shaft 48 by a chain drive 61, or any similar mechanism which will cause the valve to produce a number of puffs of air for moving the filament along the feed conduit.

The invention may be embodied in many 105 other forms, and various forms of mechanism and devices may be used to perform the operations necessary for mounting a filament in accordance with the invention.

What I claim as new and desire to secure by Letters Patent of the United States, is:

1. In a device for mounting a coiled filament by threading it thru loops on the outer ends of radial anchors on a stem, the combination of a guide having a curved conduit for the filament and radial slots across said conduit to permit the loops on the outer ends of the anchors to be placed across said conduit, a filament feeder having a straight feed groove with its outlet end in registry with the inlet end of said curved conduit, and means for sliding the filament endwise along the feed groove and said conduit to thread it thru the anchor loops across said conduit. 125

2. In a device for mounting a coiled filament by threading it thru loops on the outer ends of radial anchors on a stem, the combination of a guide having a curved conduit for the filament and radial slots across said conduit to permit the loops on the outer ends of the anchors to be placed across said conduit, a filament feeder comprising a block having a channel with an inclined bottom and a straight filament groove along the lower edge of said bottom and a cover for said channel mounted to move into and out of said block, and means for sliding the filament endwise along the feed groove and said conduit to thread it thru the anchor loops across said conduit. 70
3. In a device for mounting a coiled filament by threading it thru loops on the outer ends of radial anchors on a stem, the combination of a filament guide comprising a block having a flat surface and a curved guide groove in said surface forming a conduit, a curved cover for said groove mounted to move along the axis of curvature of said groove and also transversely of said axis to uncover and cover said groove, both said block and said cover having radial slots which extend across said groove and permit the loops on the outer ends of the anchors to be placed across said groove, and means for sliding the filament endwise along said conduit to thread it thru the anchor loops across said conduit. 75
4. In a device for mounting a coiled filament by threading it thru loops on the outer ends of radial anchors on a stem, the combination of a filament guide comprising a block having a flat surface and curved guide groove in said surface, forming a conduit, a curved cover for said groove mounted to move along the axis of curvature of said groove and also transversely of said axis to uncover and cover said groove, both said block and said cover having radial slots which extend across said groove and permit the loops on the outer ends of the anchors to be placed across said groove, said slots in said block having their bottoms sunk below the bottom of said guide groove sufficiently to hold an anchor loop in said slot coaxial with said guide groove, and means for sliding the filament endwise along said conduit to thread it thru the anchor loops across said conduit. 80
5. In a device for mounting a coiled filament by threading it thru loops on the outer ends of radial anchors on a stem, the combination of a guide having a curved conduit for the filament and radial slots across said conduit to permit the loops on the outer ends of the anchors to be placed across said conduit, the opening in the wall of each slot into said conduit being flared into the shape of a funnel which faces the advancing end of a filament passing along said guide conduit and guides it into the portion of the conduit beyond each slot, and means for applying air pressure to the filament to slide it endwise along said conduit and thereby thread it thru the anchor loops across said conduit. 85
6. In a device for mounting a coiled filament on a stem having two leads and radial anchors with loops on their outer ends by threading said filament through said loops, the combination with a filament guide having a curved guide conduit with a radial lead slot adjacent each end of said guide conduit to receive the ends of said leads and radial anchor slots intermediate said lead slots and extending across said guide conduit to permit said loops on the outer ends of the radial anchors to be placed across and in registry with said guide groove, means for sliding said filament endwise along said conduit to thread it through said anchor loops and place its ends adjoining said leads, and clamping jaws movable into said lead slots radially of said curved conduit to clamp the filament ends to said leads. 90
7. In a device for mounting a coiled filament by threading it thru loops on the outer ends of radial anchors on a stem, the combination of a guide having a curved conduit for the filament, an air channel parallel to said conduit, radial slots across said conduit to permit the loops on the outer ends of the anchors to be placed across said conduit, ports leading from said air channel and discharging across said slots into said conduit, a filament feeder comprising a block having a straight filament feed conduit with its outlet in register with the inlet of said guide conduit, an air channel parallel to said feed conduit and provided with ports leading to said feed conduit and inclined to discharge along said feed conduit toward its outlet, and means for intermittently producing a difference in pressure between said air channels and said conduits to cause a flow of air from said channels thru said ports into said conduits to drive the filament in said conduits endwise along the conduits and thereby thread it thru the anchor loops across said guide conduit. 95
8. In a device of the character described, the combination of a rotatable carrier having a stem holder, driving means for moving said carrier intermittently to place said stem holder in a series of working positions in succession, filament mounting means adjacent one of said positions for threading a filament thru loops on the ends of anchors on a stem in said stem holder, an anchor clamp at the next working position comprising a curved anvil for supporting the anchor loops and a curved press block movable toward and along the axis of said anvil to clamp said anchors between said anvil and said press block and thereby close the anchor loops, and means controlled by said driving means to actuate said filament mounting means and said anchor 100

clamp while said stem holder is stationary in said working positions.

9. In a device for mounting a coiled filament by threading it thru loops on the outer ends of anchors on a stem, the combination of 5 threading means comprising a filament guide for causing a coiled filament to follow a predetermined path and means for pushing a filament endwise along said path, stem positioning means for placing a stem with its anchor loops coaxial with said path, and common actuating means for said stem positioning means and said filament threading means.

10. In a device for mounting a coiled filament by threading it thru loops on the outer 15 ends of anchors on a stem, the combination of a stem holder for a stem having looped anchors, a threader for moving a coiled filament endwise along a predetermined path, and actuating means for positioning said stem 20 holder to place a stem with its anchor loops in registry with said path and then actuating said threader while said stem holder is so positioned.

25 In witness whereof, I have hereunto set my hand this 18th day of April, 1928.

JAKOB REGENSTREIF.
